AUTOMATIC CONTROL FOR TABULATING MACHINES

Gustav V. A. Malmros, Binghamton, and Victor O. Wilkerson, Vestal Gardens, N. Y., assignors to International Business Machines Corporation, New York, N. Y., a corporation of New York

Application September 27, 1934, Serial No. 745,694

11 Claims. (Cl. 235—61.7)

This case relates to card controlled accounting machines.

Such machines provide a group control which functions to continue normal accounting operations so long as cards of the same group are passing through the machine. When a group is exhausted, it is desired to take certain totals of the items of said group and to perform a resetting operation. To sense the fact that the cards running through the machine are of the same group, it is known to provide upper and lower card analyzers which sense selected group classifying columns of successive cards. When a group is exhausted, the next card will not have the same 15 classifying data and consequently the upper and lower group sensing analyzers will detect the difference and operate group control means to cause normal accounting operations to stop, total taking and ancillary operations to be effected, and 20 resetting to occur.

Further, the cards may be arranged in major groups having common major classifying data and a major group in turn sub-divided into minor groups of cards, each minor group having common minor classifying data. The group control means is then adapted to cause a change in machine operations upon either a change in major or minor groups but to effect different total taking and ancillary operations according to whether 25 the change is in the major or the minor group.

The group control means usually comprises one or more relays for each group data card column and a plurality of sets of contacts associated with the relays.

One difficulty with such means is the possibility among the multiplicity of contacts of one or more of them sticking. Another difficulty with a plurality of relay operated contacts is their mechanical inertia which slows up their speed of operation and requires the tabulating cards to be fed at a correspondingly reduced rate.

Accordingly, the object of the present invention is to avoid as far as possible the use of a multiplicity of relays and contacts in the group control system.

Further, this object contemplates only one relay and set of contacts for all major or minor group control columns instead of one for each such column as was formerly necessary.

Still further, the object is to provide such group control means as may operate with greater rapidity than heretofore and therefore permit speedier feed of the cards, thereby reducing the time required for obtaining an accounting result.

The latter object is particularly attained in

the present case by the use of transformers reacting to the analysis of the group data columns.

It is also an object to operate the one set of contacts for the major or minor group control only when the group changes rather than at each 5 card cycle as was formerly done, thus saving wear and tear on the several parts.

Still another object is to provide simple means for preventing back circuits through the group data analyzer should any other device of the machine be plugged across the control field. 10

Other objects will be brought out in the following parts of the description and appear from the drawings.

In the drawings:

Fig. 1 is a circuit diagram of the first form of the invention.

Fig. 2 is a circuit diagram of a second form of the invention.

Fig. 3 shows a circuit for a third embodiment 20 of the invention.

Fig. 4 shows a fourth form of the invention, and

Fig. 5 is a diagrammatic showing of a transformer element used in the scheme of Fig. 4. 25

For purposes of illustration, the invention will be explained as applied to the machine disclosed in Patent No. 1,976,617 but as will appear from the present disclosure, the invention is of more general application. Further, only as much of 30 the machine will be explained as is necessary to an understanding of the present invention.

In the first form of the invention, the upper and lower brushes are connected to the same side of the line. The first form will be described 35 with reference to the circuit diagram (Fig. 1). As shown in this figure, when switch S is closed, power is supplied to lines 10 and 11. Connected across these lines is a dynamotor DY, which supplies current at a desired voltage to the plus and minus lines 12 and 14 from which power is obtained to energize the various magnets of the tabulating machine.

To initiate operation of the machine, start key ST is depressed to close contacts 15 forming the 45 following circuit:

Circuit A.—From line 12 through closed cam contacts 16, feed clutch magnet 17, contacts 17a, relay 18, start key contacts 15, stop key contacts 19, and through contacts 20a (initially closed) to line 14. 50

Clutch magnet 17 when energized by above circuit operates its armature 17' to open contacts 17a and also to throw in the usual clutch (not shown). Opening of contacts 17' routes circuit 55

5 A through a motor relay 21 which closes contacts 21a to connect motor TM across power lines 10 and 11. This sets the motor in motion and as the feed clutch is in, cards will be fed through the machine.

10 When the first card approaches the lower brushes LB, it closes lower card lever contacts 23. Closing of contacts 23 completes a circuit (see the bottom of Fig. 1) from line 14, through contacts 23, lower card relays LCL, and through lead 26 to line 12. When the first card is closing the lower card lever contacts, the second card is closing the upper card lever contacts 24. Closing of contacts 24 completes a circuit from line 14, through contacts 24, and upper card lever relays UCL to the lead 26 of line 12.

15 A plurality of such relays LCL and UCL are provided in order to effectively control several sets of contacts. Each set of contacts closed by 20 a relay LCL will be characterized as LCL suffixed by a letter a, b, c, etc. Similarly, sets of contacts closed by relays UCL will be marked UCL suffixed by a letter a, b, c, etc.

25 The cards feed at definite distances apart so that for a short interval, the card lever contacts are open. During this interval cam contacts 29 and 30 close, and the circuits through relays LCL and UCL are maintained through these contacts and through holding contacts LCLa and 30 UCLa.

35 Energization of a relay LCL closes contacts LCLb to by-pass the start key contacts 15. The above circuit A for clutch magnet 17 is then routed through contacts LCLb, cam contacts 31 (which close at this time), and switch 32 (closed for automatic operation). The start key may now be released and the machine will be in automatic operation as long as certain card conditions are satisfied, as will be hereinafter 40 explained.

45 The control of the adding mechanism is effected by the lower analyzing brushes LB. There is one brush for each column of the card. The cards each have a plurality of columns across the card and each column has a plurality of index 50 point positions, selectively perforated to represent a designation. When a perforation occurs in the column, at a differential point of the movement of the card past the brush LB sensing the column a circuit is completed as follows:

55 *Circuit B.*—From line 14, through make and break contacts 33a and 34a (closing periods of which overlap), contacts LCLd, common conductor 35, brush LB engaging through the card 60 perforation with conductor 35, plug socket 36, a plug connection (not shown) to plug socket 37, through an accumulator control magnet 38, and common wire 39 to line 12. From socket 37, a branch circuit is formed through contacts 40 and printing magnet 42 to common line 39. The manner in which the magnets 38 and 42 respectively control accumulating and printing or listing operations in accordance with the item represented by the analyzed perforation can be 65 understood from aforesaid Patent No. 1,976,617.

70 As long as cards of the same selected group or classification are passing through the machine, the item accumulating and printing operations will automatically continue. Certain columns of the card are selected for minor group classification and a different group of columns are selected for major group classification. If the minor group classification changes the machine will automatically print a total of the items accumulated from this group. If the major group 75

classification changes, the total of all the minor group items will be printed.

Assume that columns 1 and 2 are selected for minor group control and columns 3 and 4 for major group control. Connections 43 are then made from plug sockets 44 connected to the upper brushes UB sensing the selected columns 1 to 4 of the card to plug sockets 45 and connections are also made from the lower brushes LB traversed by the selected columns to plug 10 sockets 46. The brushes LB and UB sensing the same card column will be connected respectively to plug sockets 46 and 47 of the same transformer T. The transformers which, in the present example, are connected to the brushes of columns 1 to 4 are respectively marked, for convenience, Col. 1, Col. 2, Col. 3, and Col. 4. The index point positions of the upper and lower cards pass brushes UB and LB in unison so that as long as the group classifying designation of 20 the same column of the upper and lower cards is the same, the upper and lower brushes will simultaneously feel perforations representing said classification data. Since the cards are in motion, the sensing of a perforation is momentary and as a result a surge of current, corresponding to an alternating current wave, is sent through one of the primary windings 48 and 49 of a transformer T. The circuit through primary winding 48 is as follows:

25 From line 14, through make and break contacts 33a and 34a, contacts UCLd, common conductor 35, brush UB (engaging through a perforation with conductor 35) connection 43, socket 45, primary winding 48, and through common 30 lead 50 to line 12.

The circuit through primary winding 49 is made as follows:

35 From line 14, through make and break contacts 33a and 34a, contacts LCLd, common conductor 35, brush LB (engaging conductor 35 through a perforation in the lower card), a connection to plug socket 46, primary winding 49, and through common lead 50 to line 12.

40 The current flows through coils 48 and 49 in opposite directions. Hence, to produce opposing fluxes, the coils are wound in the same direction. When simultaneously energized, the coils will produce oppositely directed fluxes which will neutralize each other and have no effect on the secondary winding 52 of the transformer. Thus, as long as the class data on upper and lower cards agree, secondary windings 52 will remain inert and no change in machine operation 50 will occur.

45 It is important that the upper and lower brushes of the same column sense perforations of the same value and therefore in corresponding index point positions in exact synchronism. The upper and lower cards may, however, not be 60 feeding in perfect synchronism because of unequal slippage of the card relative to the feeding means or for some other reason and as a result one of the brushes would sense a perforation in one card before the other brush senses a like 65 perforation in the other card.

70 As the reaction of the primary winding to the sensing of a perforation by a brush is extremely rapid, one of the primary windings might, therefore, be energized before the other and as a result, secondary 52 of the same transformer would be undesirably energized. It is to avoid this possibility that the circuits through the primary windings must be made through contacts 33a and 34a in series.

Make and break contacts 33a and 34a are operated by notched disks 33 and 34. There is one notch in each disk for each index point position of a card column. When the contact blades 33' and 34' drop into a notch, the contacts 33a and 34a close. Thus during rotation of a disk, the contacts will make and break as many times as there are index point positions in a card column. The disks 33 and 34 are so timed with respect to each other that one of the contact blades 33' or 34' will move into and out of a notch before the other contact blade but for an instant they will both be in notches at the same time so that the circuits through contacts 33a and 34a in series can be made at a sharply defined momentary point of the cycle falling within the sensing periods of like index point positions of the upper and lower card levers by the upper and lower brushes. The circuits through primary windings 48 and 49 are therefore timed by make and break contacts 33a and 34a to make in exact synchronism.

It may be well, at this point, to explain the theory of operation as it relates to the inducing 25 of a current flow and the direction of current flow in the transformed secondary. The dynamotor DY, in the present case, supplies direct current to opposite lines 12 and 14. When the brush at an analyzing station is on an unperforated or 30 dead portion of a card, there is no circuit formed therethrough. When the brush moves into a perforation and engages the common conductor of the analyzing station, a circuit, such as traced hereinbefore, is formed through the connected 35 primary 48 or 49. Although the primary current is direct current, the fact that the latter starts at zero (or a minimum) at the moment the circuit makes and increases to its maximum value as the circuit is fully made produces a fluctuating current 40 impulse. This current fluctuation is a rising current, threading both primary and associated secondary with an increasing flux. The increasing flux induces an E. M. F. in the secondary to produce a current flow therein in a 45 certain direction. After the primary circuit was fully made, the primary current fluctuation stops and a constant flux is threading the transformer coils so that no current is induced or flowing in the secondary. When the primary circuit breaks, 50 due to the perforation leaving the brush or the opening of contacts 33a and 34a, the flux threading the transformer windings collapses, causing an induced current to flow in the secondary in a direction opposite to the direction of flow during 55 the building up of the flux.

For practical purposes, and in the ultimate effect on control of the machine, only the current induced by the building up of the flux need be considered as this occurs first, because of the 60 brush moving into a perforation, and takes effect before the occurrence of the induced current resulting from the collapsing flux. Accordingly, consider, for the present, only the results of the brush moving into a perforation with consequent 65 increasing flux threading the transformer windings.

Assume now that a change in the minor group classification occurs. As a result, the upper and lower brushes do not simultaneously sense perforations. Consequently one or the other of the brushes feeling the same minor classification column sends an impulse through the connected primary winding while the other brush does not send an impulse to its connected primary winding. 70 The impulse thus sent is an increasing current

flow which causes a flux to build up, threading the primary connected to the active perforation feeling brush.

Since only one primary winding is energized a current is induced in one direction in the secondary winding. Thus if primary winding 48 is energized, then a current will be induced in secondary 52 which will be in a direction which, for convenience, may be referred to as the forward direction permitting its passage through a rectifier 53 while if primary 49 is energized, the current induced in secondary 52 will be in a direction which, for convenience, may be called the reverse direction permitting its passage through a uni-directional current valve or rectifier 54. The rectifiers may be of any suitable type such as of vacuum tube, photocell, crystal, or dry copper oxide disk type. Assume that the upper brush is sensing a perforation while the lower brush is not, then primary 48 will be energized to induce current through secondary 52 to form the following circuit:

From one end of secondary 52, through rectifier 53, pick-up coil 55 of a duo control relay R, plug socket 56, plug connection 57, and through 25 serially connected plug socket 58 to the opposite end of the secondary 52.

Should the lower brush be sensing a perforation while the upper brush is not, then the circuit will be as follows:

From one end of secondary 52, through plug 30 sockets 58, connection 57, the other pick-up coil 550 of the relay R, and through rectifier 54 to the opposite end of the secondary.

The purpose of the rectifiers is to prevent 35 perforations of like value in different card columns from neutralizing each other's control of the relay R. For example, with number 13 perforated in columns 1 and 2 of the lower card and number 31 in columns 1 and 2 of the upper 40 card, the relay R would not be activated in the absence of the rectifiers although these classification items do not agree. To understand this, consider column 1 alone with the upper brush sensing a "3" in the column while the lower brush 45 is dead, resulting in energization of the primary coil 48 of column 1 transformer T at the "3" point of the card reading cycle. The primary coil 48 will thereupon induce a current in one direction in its secondary 52. With absence of 50 rectifiers, this secondary will send current through both coils 55 and 550 of relay R in one direction. At the same time, if a lower brush is sensing a "3" in column 2 of the lower card while the upper brush of column 2 of the upper 55 card is dead, then primary 49 of column 2 transformer will be energized, inducing current in its secondary 52 in opposite sense to the current induced in column 1 secondary 52. Column 2 secondary will therefore send current through both coils 55 and 550 in an opposite direction to the current in said coils flowing from the secondary of column 1 transformer. The opposing currents will neutralize each other and the relay R will not be activated as it should be on 60 a change in a minor classification data. By using rectifiers 53 and 54 in above example, current from column 1 transformer is allowed to pass only by rectifier 53 resulting in energization of coil 55 alone while current from column 65 2 transformer can pass only through rectifier 54 to energize coil 550 alone.

While the currents in these coils are in opposite sense, the fact that they are oppositely wound causes their energization to assist each other.

Energization of coil 55 or 550 or both, results in closing holding contacts 62 and opening minor control contacts 63.

Closure of contacts 62 forms a circuit through holding coil 64 of minor control relay R as follows:

From line 12, through wire 50, contacts 62, coil 64, and cam contacts 66, to line 14.

Energization of coil 64 holds contacts 62 closed and contacts 63 open until cam contacts 66 break near the end of the card cycle.

In a similar manner, when major classification items in selected columns 3 and 4 do not agree, then current will flow from the secondaries of transformers T of columns 3 and 4 through plug wire 57' to socket 56' of major control relay R' and the latter will act to close contacts 62' and open contacts 63'.

The currents flowing in the secondaries as a result of the fluxes building up when the brushes move into perforations to make the primary circuits have been considered above. In practice, only these currents are important as they occur first and result in energization of holding coil 64 and opening of control contacts 63 and/or 63' before the primary circuits break.

When the primary circuit breaks, the flux threading the secondary collapses, inducing a current therein in the opposite direction to that of the current previously induced by the increasing flux. Considering only the minor control relay R, with opening of the primary circuit through primary 48, the collapsing flux induces a current flow in the associated secondary 35 52 in the direction previously characterized as reverse. This reverse current flows through rectifier 54 to relay coil 550. With opening of the primary circuit through primary 49, the current induced in the secondary is in the forward direction, which through rectifier 53, flows through relay coil 55. Energization of one or both coils 55 and 550 results, tending to open contacts 63. But the latter contacts are already open because of previous energization of the coils due to 45 the building up of flux in the transformers, so that the later energization of the coils is without any practical result.

Only when both the major and minor group classifications on successive cards agree, will contacts 63 and 63' remain closed. These contacts are in series and if either is open during the card cycle, a change in machine operation will occur, as will be hereinafter described.

Initially the circuit through control relay 20 55 is momentarily made as follows when cam contacts 67 and 67' close for a brief interval:

Circuit C.—From line 12, through cam contacts 67, switch 68, cam contacts 67', relay 70, relay 71, line 72, control relay 20, line 73, terminal 60 730, cam contacts 74 and 75, terminal 760 and lead 76 to line 14.

When above circuit makes, magnet 10 is energized to close contacts 70a to shunt out cam contacts 67 and 67'.

Cam contacts 74 and 75 open for a brief interval of each card cycle after the item perforation positions of the cards have passed the analyzing brushes. When cam contacts 74 and 75 open, circuit C must be maintained through minor control contacts 63 and major control contacts 63'. The shunt path of circuit C through the major and minor control contacts is as follows:

From terminal 730, through line 71, minor control contacts 63, lines 78, 79, major control

contacts 63', line 80, and through contacts UCLe, to terminal 760.

Briefly, circuit C which energizes control relay 20 is initiated by momentary closure of cam contacts 67 and 67'. The circuit energizes relay 70 to close contacts 70a and by-pass cam contacts 67 and 67'. During the period of the cycle in which the brushes search for classification data, the circuit is established through cam contacts 74 and 75. After the searching period, the 10 cam contacts 74 and 75 open and the circuit must be made through major and minor control contacts 63' and 63, respectively. However, if during the searching period, a disagreement in minor classification data has occurred, then as 15 above explained, minor control contacts 63 open and the circuit is broken. Or if a major group change has occurred, the major control contacts 63' open and circuit C is likewise broken.

With circuit C broken, then relay 20 is de- 20 energized and its contacts 20a are open. Accordingly, circuit A is broken and clutch magnet 11 and motor control relay 21 are deenergized. Motor TM will therefore stop and the card feed 25 will be interrupted.

The deenergization of relay 20, which occurs upon the group change, as above explained, causes contacts 20a to open and contacts 20b to close. Now with switch RS closed, the following circuit is formed:

From line 14 through contacts 20b, switch RS, cam contacts 82 (momentarily closed near the end of the cycle), magnet 83, and closed cam contacts 84, to line 12.

Magnet 83 is thereby energized and closes contacts 83a connected through line 76 directly to line 14 to shunt out cam contacts 82, switch RS, and contacts 20b. When a minor group change occurred, circuit C was opened and magnet 71 in this circuit was deenergized, thereby permitting 40 contacts 71a (above cam 84) to close. With both contacts 71a and 83a closed the following circuit is made:

From line 12, through contacts 71a, normally closed contacts 87, reset clutch magnet 88, closed 45 cam contacts 89, contacts 83a, and line lead 76, to line 14.

Energization by above circuit of reset clutch magnet 88 connects the reset motor RM to the read out, total printing, zeroizing mechanisms to 50 operate as explained in aforesaid Patent No. 1,976,617. Magnet 88 also closes contacts 88a to form the reset motor circuit as follows:

From line 10, through reset motor RM, magnet 92, line 93, contacts 88a, line 94, and line 95, to 55 line 11.

This circuit causes operation of the reset motor. Shortly after the reset motor starts on its cycle, cam contacts 96 close to shunt out contacts 88a.

As explained above, a change in minor classification opened circuit C by causing minor control relay R to open minor control contacts 63. Consequently, relay 70 in circuit C is deenergized and contacts 70a open. Circuit C can now be re-established only through its initial path which is 60 through cam contacts 67 and 67'. These latter close near the end of the reset cycle and circuit C is again made so that magnet 71 is energized to open contacts 71a.

Cam contacts 84 also open at this time so that 70 the circuit through reset clutch magnet 88 and relay magnet 83 will be broken. Consequently, the reset and totaling mechanism will be de-clutched from the reset motor RM and contacts 88a will open to break one of the circuit paths 75

through the reset motor. The reset mechanism coasts to home position and at the end of its one cycle, causes cam contacts 96 to break, opening the remaining circuit path through the reset motor.

During the reset cycle, the printing of only the minor totals from selected accumulator banks and the zeroizing of the latter takes place in a manner detailed in aforesaid patent.

- 10 When a major group change occurs, not only is the minor total taken but also the printing of major total from selected accumulator banks and their zeroizing is effected. When a change in major group control takes place, major control 15 relay R' is energized, opening contacts 63' which thereupon breaks circuit C. As a result, the reset and minor control operations take place in exactly the same manner as before explained. At the same time, opening of contacts 63' breaks 20 a circuit through a control relay 100. This circuit had been initiated by closure of cam contacts 67 in the preceding reset cycle, as follows:

From line 12, through contacts 67, relay 100, terminal 101, cam contacts 75, terminal 760, and 25 through lead 76 to line 14.

Energization of magnet 100 closes contacts 100a to shunt out cam contacts 67 which shortly thereafter open. When cam contacts 75 open, the circuit through magnet 100 must be completed through contacts 63' as follows:

From terminal 101, through line 79, contacts 63', line 80, contacts USLe, and to terminal 760.

Should a major group change occur, then major control relay R' will open contacts 63', 35 breaking the latter circuit path of relay 100 so circuit C opens. The opening of circuit C results in resetting operations as before explained.

Relay 100 being deenergized, contacts 100a open and contacts 100b close. Closing of contacts 100b controls a major total printing operation, in a manner outlined in aforesaid patent.

Figure 2 shows a form of the invention in which the upper and lower brushes are connected on opposite sides of the current supply. Thus, 45 with closure of cam contacts 66', if the upper brush 1 is sensing a perforation, say 3, in column 1 of the upper card then the circuit will be as follows:

From plus line 12', through contacts 66', make 50 and break timing contacts 33a-1, common conductor 350', column 1 upper brush UB-1, primary transformer coil 110, and lead 111 to minus line 14'. If the lower brush LB-1 is simultaneously with above occurrence sensing a "3" perforation in column 1 of the lower card, the following circuit will form:

From plus line 12' through lead 112, primary transformer coil 113, brush LB-1, common conductor 35', lower card lever contacts 114, and 60 make and break timing contacts 34a-1 to minus line 14'.

The function of contacts 33a-1 and 34a-1 is the same as that of contacts 33a and 34a of the first form of the invention.

65 Coils 110 and 113 are wound oppositely to each other so that with the simultaneous completion of circuits therethrough they will have no effect on secondary transformer coil 115. Should only one brush LB or UB in the same column order be sensing a perforation, then one of coils 110 or 113 will be active while the other would be inactive and an induced current will form in secondary 115. The connections of the secondary coils to the rest of the machine is the same as 70 in Fig. 1 so that energization of these secondaries

will produce a change in machine control and total and reset operations in the same manner as described in connection with the first form of the invention.

In Figure 3 is shown a third form of the invention, in which the upper and lower brushes are on the same side of the current supply and in which only one primary transformer coil 116 to each transformer is necessary for each pair of correlated upper and lower brushes. This single 10 primary coil 116 is placed in the balance line of a Wheatstone bridge arrangement in which resistances r and r' are equal. Thus, if the upper and lower brushes of the same column UB' and LB' are reading perforations of the same value, 15 circuits will form through UB' as follows:

From plus line 12-1, through resistance r, rectifier 118, plug connection 119, brush UB', common conductor 350-1, upper card lever contacts 120, and through make and break contacts 20 33a-2 and 34a-2, to line 14-1. A second parallel circuit will form from line 12-1 through resistance r', primary coil 116, and as before.

This circuit through primary coil 116 is in one direction.

Simultaneously with above circuits, other circuits will form through lower brush LB' as follows:

From plus line 12-1, through resistance r', rectifier 118', brush LB', common conductor 35-1, 30 lower card lever contacts 121, and make and break contacts 33a-2 and 34a-2, to line 14-1. A second parallel circuit is formed from line 12-1 through resistance r, primary coil 116, LB', and as before.

This circuit through primary coil 116 is in the opposite direction to the previously described circuit through the primary.

Resistances r and r' being equal, these opposing circuits through 116 neutralize each other so that 40 coil 116 will not be energized. The Wheatstone bridge is then in balanced condition. Should either UB' or LB' be sensing a perforation while the other is not, the current in coil 116 is in one direction and not opposed by an opposite current. 45 Consequently, coil 116 will be energized and induce current in secondary 122. The connections of the secondary to the rest of the machine are the same as in Fig. 1 so that its energization will produce the same results as in the first form of 50 the invention.

Rectifiers 118 and 118' are provided in the primary circuits to prevent back circuits when other devices of the machine are plugged across the control field to the group control analyzing brushes.

Figs. 4 and 5 show still another form of the invention. In this form, the duo control relay R-1 does not require a double pick-up winding such as 55 and 550 of duo control magnet R of Fig. 1. This is because the current induced in the secondaries 60 of the transformer is in only one direction regardless of whether the upper or lower brush is the active one.

Therefore, should a lower brush in one column 65 be sensing the same value perforation as an upper brush in another column, then the currents induced in the secondaries of the different corresponding transformers will flow in the same direction through the single activating coil of the control relay.

To understand the above, consider first the circuits when the upper and lower brushes UB-A and LB-A are sensing the same value perforation in the same column of the upper and lower cards.

A circuit will form through the upper brush as follows:

From plus line 12-2, through common line 124, primary winding 125, plug connection 126, upper brush UB-A, common conductor 350-2, line 127, and make and break timing contacts 33a-3, to minus line 14-2.

One circuit through lower brush LB-A will be from plus line 12-2 through make and break timing contacts 34a-3, common conductor 35-2, brush LB-A, rectifier 128, and primary winding 129 to minus line 14-2. Another circuit through LB-A will be from plus line 12-2, through contacts 34a-3, conductor 35-2, brush LB-A, primary coil 130, connection 126, UB-A, conductor 350-2, line 127, and contacts 33a-3, to minus line 14-2. Coils 125 and 129 are wound in the same direction but opposite to the direction of winding of coil 130, thus with agreement in the same column, coils 125, 129 and 130 will all be energized and the direction of flux produced by the current in each will be as indicated by the arrows in Fig. 5.

When the coils 125, 129, and 130 are singly energized upon brushes UB and LB sensing corresponding perforations, the coil 130 is designed to produce a flux balancing the sum of the fluxes of coils 125 and 129. Accordingly, the secondary coil 132 will not be effectively energized.

When only the upper brush is alive, then the circuit can be made only through coil 125. When only the lower brush is alive, coil 129 alone will be energized. In either case, since both coils produce fluxes in the same direction, the current induced in secondary winding 132 will be in only a single direction, regardless of whether the upper or lower brush is alive. Hence if a lower brush in one column is sensing a "3" perforation simultaneously with the sensing of a "3" perforation by the upper brush of a different column, the current in the secondaries 132 belonging to the different columns will be in the same direction. Thus, the occurrence of a 13 in one card and a 31 in the other card will not counteract each other in their control of the secondaries of the associated transformers and no one-way valves or rectifiers are needed as in Fig. 1. Hence only one pick-up coil 133 in the group control relay R-1 is required.

The only reason for providing rectifiers 134 in the secondary circuits of Figs. 4 and 5, is to prevent the current produced by one secondary coil from flowing back into another secondary coil to be thereby dissipated. The rectifiers 134 permit the current from a secondary 132 to flow only into the pick-up winding 133 of the control relay. Of course, with the rectifiers omitted, the available current energy produced by one secondary and distributed to the other secondaries and coil 133 is less than if the current flow were confined to coil 133 by the interposition of the rectifiers between one secondary and the other secondaries. Thus, with omission of the rectifiers, relay 133-620 would have to be designed to operate with a smaller supply of current energy than when the rectifiers are included.

Holding coil 640, cam contacts 660, holding contacts 620, and machine control contacts 630 function in the same way as the respectively corresponding elements 64, 66, 62, and 63 of Fig. 1. The above explanation of the form shown in Figs. 4 and 5 has taken into account only the effects of the increasing fluxes in the transformer windings when the brushes entered the perforations and made the primary circuits. When the pri-

mary circuits break, the fluxes threading the transformer windings collapse. If the group control perforations agree, then the decreasing fluxes counteract each other. If the control perforations of corresponding upper and lower card columns disagree, the decreasing flux threading the associated secondary 132 tends to produce a current flow therein in a direction opposed by rectifier 134. Thus, the collapsing flux, resulting from the brush leaving the perforation does not disturb the previous energization of holding coil 640. Even were rectifier 134 dispensed with, the decreasing flux would still fail to disturb the energization of coil 640. Thus, with rectifier 134 omitted, the decreasing flux would produce a reverse current flow or one in a direction opposite to the direction of the current produced by the increasing current flow. Energization of coil 133 by the reverse current flow would tend to reopen contacts 620. But the holding coil 640, being energized, would maintain contacts 620 closed.

The purpose of rectifiers 128 between the lower brushes LB and the windings 129 and 130 is to prevent the formation of back circuits through the lower brushes when other devices are connected to the lower brushes.

While the invention has been disclosed as embodied in the several illustrated forms, it is understood that variations and changes may be made within the field of mechanical skill without departing from the scope of the invention. We therefore wish to be limited only by the following claims.

What is claimed is as follows:

1. In a machine in which cards bearing group designations are run through in groups; the combination of electrical means for comparing the designations of successive cards to detect a group change and including a transformer primary effectively energized upon the detection of a group change, a transformer secondary coupled to said primary and in which current is induced by effective energization of aforesaid primary, and a control device for the machine in series with said secondary and varied in operation by said secondary when current is induced therein upon a group change.

2. In a machine in which cards bearing group designations are run through in groups; the combination of electrical means for comparing the designations of successive cards to detect a group change and including a transformer primary having opposing primary windings simultaneously energized to neutralize each other upon agreement between the designations of said successive cards and singly energized upon non-agreement between the designations denoting a group change, a transformer secondary coupled to said primary windings and in which current is induced by energization singly of said primary windings, and a control relay for the machine in series with the secondary and varied in operation by said secondary when current is induced therein.

3. In a machine in which cards bearing group classifying perforations are run through in groups, the perforations of successive cards agreeing except upon a change in group; the combination of spaced analyzers for concurrently sensing agreeing group perforations of successive cards, a transformer including a pair of opposed primary windings, each in circuit with a different one of the analyzers to be energized when a perforation is sensed, both said windings being simultaneously energized upon concurrent sensing

- of agreeing perforations by both analyzers to neutralize each other, said windings being singly energized upon failure of the analyzers to concurrently sense perforations upon a group change, 5 a secondary in said transformer in which current is induced by the energization of either of said windings singly, a relay in circuit with the secondary and energized by the current flow in the secondary, and means controlled by energization 10 of the relay for varying the operation of the machine.
4. In a machine in which cards having group designating perforations are run through in groups; the combination of analyzers for sensing 15 the group designating perforations of successive cards while the latter are in motion, both analyzers concurrently sensing the perforations if they agree and one or the other analyzer sensing perforations before the other if the perforations do 20 not agree, a transformer having a primary and secondary with the primary controlled by the analyzers to provide a current flow through the secondary in either of opposite directions in accordance with which analyzer senses perforations 25 first, a pair of relay coils conductively connected to the secondary, uni-directional current valves in series with each relay coil to pass current flow from the secondary to only one of said coils depending on its direction, and means controlled by 30 either relay coil upon its receiving a current flow from the secondary for varying operation of the machine.
5. In a machine in which cards bearing group designating perforations in a plurality of columns 35 are run through in succession; the combination of a series of analyzing brushes one to each group designating column to sense one of a pair of such successively running cards, a second series of analyzing brushes one to each group designating 40 column to sense the other of the pair of such successive cards, a plurality of transformers, each having its primary in series with and controlled by one pair of corresponding brushes of both series to produce a current flow in the secondary in either of opposite directions depending on 45 which of the pair of corresponding brushes senses perforations first, a pair of relay coils conductively connected to the secondaries of all the transformers, uni-directional current valves interposed in the circuit between each of the secondaries and 50 the relay coils to direct the flow from any secondary in one direction to one coil and a simultaneous flow from another said secondary in an opposite direction to the other coil, and means controlled by the coils for varying machine operations.
6. The invention as defined in claim 5, said relay coils being oppositely wound to assist each other when simultaneously energized by the reception of oppositely flowing currents from the 55 transformers, and said last-named means including control contacts commonly operated by both said coils.
7. In a machine in which cards bearing group 60 designating perforations in several columns are run through in groups; the combination of means for analyzing the group designating columns of successive cards to detect a group change, a plurality of transformers, one to each like pair of 65 group designating columns of successive cards, each transformer having a primary and a secondary with the primary controlled by the analyzing means to produce a current flow in the secondary when the analyzing means detects a 70 group change in the like columns of the successive 75 cards corresponding to said transformer, a relay in circuit with all the secondaries and energized by the current flow of any one or more of said secondaries, and means controlled by the relay upon its energization to vary machine operation.
8. In a machine in which cards bearing group 80 designations are run through in groups; the combination of means for comparing the designations of successive cards to detect a group change and including a transformer primary and a Wheatstone bridge circuit having said transformer primary arranged in its balance line, the circuit being connected at opposite sides to the comparing means to be in balance when the comparing means fails to detect a group change whereby the transformer primary remains unenergized when the successive cards belong to the same group, the circuit being unbalanced upon the comparing means detecting a group change to thereby energize 85 said primary, a secondary coupled to said primary and in which current is induced by energization of the latter, and a control device for the machine in series with said secondary and varied by the current in said secondary.
9. In a machine in which cards bearing group 90 designations are run through in groups; the combination of spaced analyzing brushes for sensing the designations of successive cards, a transformer having a pair of similarly wound primary coils, one in circuit with one of the brushes and the other in circuit with the other brush to be simultaneously energized upon the brushes sensing agreeing designations, a third primary coil wound oppositely to the first-mentioned primary coils and in circuit with both said brushes to be simultaneously energized with the latter coils under control of said brushes when the designations agree to thereby neutralize the combined effects of the latter coils, either one of the first-mentioned coils being energized alone when the 95 brushes sense unlike perforations while the other primary coils remain unenergized, a secondary coupled to the primary coils and in which an E. M. F. is induced by energization of either one of said first-mentioned coils alone upon failure 100 of designations to agree, and means controlled by the secondary when energized for varying machine operation.
10. The invention according to claim 9 in which the designations are arranged in several 105 card columns; there being one pair of analyzing brushes for each card column and one such transformer to each pair of brushes, the secondaries of said circuits being arranged in parallel circuit, and uni-directional current valves between the 110 transformer and one side of said circuit to prevent the induced current from one secondary flowing into another.
11. In a machine in which cards bearing group 115 data are run through in groups; the combination of electrical means to compare group data of successive cards to detect a group change and including a transformer primary effectively energized upon occurrence of a group change, a transformer secondary in which current is induced by 120 energization of the transformer primary, a uni-directional current valve in series with the secondary, and an electrical control device in circuit with the secondary and valve to which current 125 from the secondary in only one direction is permitted to pass by said valve to energize said device upon a group change.
